US00D727877S

(12) **United States Design Patent**
Seoc

(10) **Patent No.:** **US D727,877 S**
(45) **Date of Patent:** **** Apr. 28, 2015**

(54) **DOCKING SPEAKER**

(71) Applicant: **Ho-Young Seoc**, Yongin (KR)

(72) Inventor: **Ho-Young Seoc**, Yongin (KR)

(73) Assignee: **Samsung Electronics Co., Ltd.**,
Suwon-si, Gyeonggi-do (KR)

(**) Term: **14 Years**

(21) Appl. No.: **29/450,856**

(22) Filed: **Mar. 25, 2013**

(30) **Foreign Application Priority Data**

Nov. 23, 2012 (KR) 30-2012-0056046

(51) **LOC (10) Cl.** **14-03**

(52) **U.S. Cl.**

USPC **D14/216**; D14/209.1

(57) **CLAIM**

The ornamental design for a docking speaker, as shown and described.

DESCRIPTION

FIG. 1 is a top front perspective view of a docking speaker showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a top front perspective view thereof showing the present docking speaker with its connector exposed;

FIG. 9 is a front elevational view thereof showing the present docking speaker with its connector exposed;

FIG. 10 is a rear elevational view thereof showing the present docking speaker with its connector exposed;

FIG. 11 is a left side elevational view thereof showing the present docking speaker with its connector exposed;

FIG. 12 is a right side elevational view thereof showing the present docking speaker with its connector exposed;

FIG. 13 is a top plan view thereof showing the present docking speaker with its connector exposed; and,

FIG. 14 is a bottom plan view thereof showing the present docking speaker with its connector exposed.

The broken lines depict environmental subject matter only and form no part of the claimed design.
